CLAIM

The ornamental design for an electronic device with animated graphical user interface, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a display screen or portion thereof with animated graphical user interface showing a first image of the claimed design;

FIG. 2 is a second image thereof;

FIG. 3 is a third image thereof;

FIG. 4 is a fourth image thereof;

FIG. 5 is a front view of another embodiment of a display screen or portion thereof with animated graphical user interface showing a first image of the claimed design;

FIG. 6 is a second image thereof;

FIG. 7 is a third image thereof;

FIG. 8 is a fourth image thereof; and,

FIG. 9 is a front view of an electronic device having a display screen with the animated graphical user interface of FIG. 1 applied to the display screen. The animated graphical user interface design of FIGS. 2-4 and 5-8 may be similarly applied thereto.

The broken lines in the figures show a display screen or portion thereof, or an electronic device having a display screen, and form no part of the claimed design.

The appearance of the animated image sequentially transitions between the images shown in FIGS. 1-4 and FIGS. 5-8,

(Continued)

respectively. The process or period in which one image transitions to another forms no part of the claimed design.
